UNITED STATES PATENT OFFICE.

WLADYSLAW NARUSZEWICZ, OF NORTH ANDOVER, MASSACHUSETTS.

SWIMMING-GLOVE.

1,299,007.

Specification of Letters Patent.

Patented Apr. 1, 1919.

Application filed October 5, 1918. Serial No. 256,980.

To all whom it may concern:

Be it known that I, WLADYSLAW NARUSZEWICZ, a citizen of Russia, residing at North Andover, county of Essex, and State 5 of Massachusetts, have invented certain new and useful Improvements in Swimming-Gloves, of which the following is a specification.

This invention relates to improvements in 10 devices for assisting in the propulsion of swimmers, and has as its special object the provision of a device which is readily attached to the extended fingers and hands of the operator in such manner as to form a 15 web-like structure whereby propulsion in the water is easily effected.

A still further object is to provide such devices having reinforcing elements at their outer extended edges so as to hold the web 20 in a substantially rigid manner.

These and other like objects are attained by the novel construction and combination of parts hereinafter described and shown in the accompanying drawings, forming a 25 material part of this disclosure and in which—

Figure 1 is a transverse sectional view taken on line 4—4 of Fig. 3.

Fig. 2 is a transverse sectional view taken 30 on line 5—5 of Fig. 1, and

Fig. 3 is a perspective view showing one of the web elements and indicating the manner in which it may be attached to the operator's hand.

Fastened upon one side of the element 22, 35 are rings, respectively 28 and 29, the former being adapted to engage with the thumb, while the latter may be placed upon the little finger, thereby securing the web in an effective manner to the hand. 40

In order to strengthen and reinforce the outer edge of the flexible material, the same is rolled upon itself as at 30, and inclosed at one end within the tubular reinforcement 30, is a curved tube 31, while at the other 45 end is secured a similarly curved rod 32, slideable within the tube 31 telescopically, thereby permitting the web to be collapsed and closely folded so as to enter the pocket or envelop 20 when not required in use. 50

Having thus described my invention and set forth the manner of its application and use what I claim as new and desire to secure by Letters Patent, is—

In a swimming device, the combination 55 with a segmental shaped web, means for securing said web, at the smaller end thereof, rings fastened upon said web along its lateral edges, a turned edge at the larger end of said web, a tube secured at one end within 60 said edge, and a rod secured at the other end, said rod being enterable within said tube whereby said web may be collapsed.

In testimony whereof I have affixed my signature.

WLADYSLAW NARUSZEWICZ.
